GARMENT

Harry Kantor, Woodmere, N. Y., assignor to Paul Prescott, Inc., New York, N. Y., a corporation of New York

Application July 13, 1946; Serial No. 683,505

5 Claims. (Cl. 2—74)

1.

This invention relates to garments in general, and especially to what may be considered free-action garments; wherein means are provided for assuring an unrestricted movement of both the arms and the upper body portion of the wearer.

One of the objects of the present invention is to provide in the upper portion of garments, above the waist, a so-to-speak self-closing, or self-folding, pleat structure, composed of two outer sets and an inner set of pleats, the outer set of pleats extending from points at the back and both sides of the waist toward approximately half-way of the back sleeve-shoulder portions and from about midway of the shoulder portions in the front to points at the front and sides of the waistline.

Another object of this invention is to provide such self-closing pleats with stiffened or reinforced edges, which latter facilitate and induce an automatic closing, or folding, against one another of the garment material elements forming the pleats, when the garment is not subjected to stresses caused by upward, sidewise or forward movements of the sleeves.

Another object of the present invention is to provide in combination with the upper portion of a garment, self-closing pleats arranged in front and back thereof, and wherein the pleats are so constructed as to automatically fold upon themselves when not under stress and to readily unfold when subject to stress caused by the movement of the arms, and wherein specially designed inserts are provided at the arm pit portion of the sleeve, which inserts extend into the interior pleat portions and are adapted to facilitate the opening of the pleats when the sleeves are moved from their normal downward position to forward, sidewise or elevated positions.

Another object of this invention is to provide self-closing pleats with reinforced or stiffened edges, wherein the reinforcement or stiffening is effected by one or more continuous courses of stitching along the edges of the pleats, and which stitching extends in the back pleats from points in back of the waistline, towards approximately the middle of the shoulder portion, then over the shoulder to about the middle of the shoulder portion at the front, and from thereon along the frontal pleats to points at the front of the waistline.

The foregoing and other objects and important

- advantages of the present invention will become more fully understood from the ensuing description in conjunction with the accompanying drawings, wherein:
5. Fig. 1 is a front elevation of a garment equipped with self-closing pleat structures in accordance with the present invention;
10. Fig. 2 is a rear view thereof;
10. Fig. 3 is an enlarged detail view of the pleat construction including the arm pit insert;
10. Fig. 4 is a plan or bottom view of the arm pit sleeve portion; and
15. Fig. 5 is an enlarged section taken on line 5—5, through Fig. 3.
15. Referring now to the drawings, numeral 10 denotes a woman's dress which buttons in front at its upper half, and wherein the portion of the garment above the waistline belt 11 is so constructed as to produce two openable, continuous front areas or front panels 12 and a continuous back area or back panel 13, and wherein both front and rear areas have reinforced edge formations 14 and 15, respectively, and which front and rear areas terminate and are joined at about mid-way of and form sleeve shoulder portions 16, beneath which are provided arm openings 16'. Attached to the edges of opening 16' and depending from them are sleeves 16''. Reinforced edge formations 14 and 15 of the front and rear panels are partly attached to the upper edge portions of the arm openings and of the sleeves, as indicated in front at 17 and in back at 18. The reinforcement of these edge foundations consists of one or more stiffening courses of stitching 19, which stitching courses extend over the shoulder tops as indicated at 20.

Front and rear portions 12 and 13 are connected between their stitch-reinforced edges 14 and 15 by an accordion arrangement of multiple pleats, as clearly indicated in Fig. 5. That pleat arrangement consists of two exterior pleats 21 and 21' and a single interior or central pleat 22, which latter pleat is substantially deeper or wider than outer pleats 21 and 21'. Exterior pleat 21 is composed of inwardly and outwardly directed sections 21a and 21b, while exterior pleat 21' is constructed of similar inwardly and outwardly directed sections 21'a and 21'b. Central pleat 22 is composed of two inwardly directed sections 22a and 22b, the interior edges of which sections

are sewed together by reinforcing stitching 22' which latter serve as reinforcements for their joined edges to normally hold sections 22a and 22b of center pleat 22 in close adjacency. The outer edges of pleat sections 22a and 22b are not stitched and connect with outwardly directed pleat sections 21b and 21'b of the exterior pleats 21 and 21'.

It will be noted that the interior edges of the exterior pleats connecting their respective inwardly and outwardly directed sections are also not stitch-reinforced, similar to the outer edges of interior pleat 22, whereby these unstitched connecting edges are rendered more pliable and less resistant to a temporary displacement than the stitch-reinforced, joined inner edges of interior pleat 22 and the outer edges of exterior pleats 14 and 15. Thus when the accordion pleat arrangement is momentarily subjected to an outward pulling action, the unstitched pleat edges will readily unfold, but will just as readily re-assume their original position when the pulling action ceases. That reverting of the pleats to their normal position is due to reinforcing stitching 22' and 19 at the joined edges of interior fold 22 and at the outer edges of exterior folds 14 and 15, respectively.

At the arm pit portions of the sleeves there are provided inserts 23 which are substantially diamond-shaped, as clearly seen in Fig. 4, the outward edges 24 of which extend into the sleeves, while the inner edges 25 are connected with sections 22a and 22b of central pleat 22, as clearly seen in Fig. 4.

Exterior pleats 21 and 21' are intended to automatically assume their self-closing position as exaggeratedly illustrated in Fig. 5. When, however, the sleeves are brought from their normal downward position to an upward, forward or side-wise position, inserts 23 will pull the interior pleat 22 outwards, and outer exterior pleats 21 and 21' will immediately open, thereby effecting complete freedom in the action of movement of both arms and of the upper body portion. When the strain caused by the upward movement of the sleeve is relieved, inserts 23 revert to their normal inward position, and the reinforced edges of the several pleats bring their respective sections to their normal, folded or closing position.

The aforescribed construction of garments, although being primarily intended for wear by women engaged in sports such as bowling, tennis, golf, horseback riding, etc., the garment presents a very neat and dressy appearance for everyday use. Due to the fact that the pleats of the garment automatically assume their normal, closed or folded position when the sleeves are permitted to depend naturally, the features for providing free movement of the wearer's arms and the upper body portion remain hidden from view. Thus the garment may be used either for sports or for street wear, and obviates change of clothing heretofore necessary for such dual purposes.

While in the foregoing a specific construction of the automatically folding pleat structure is presented, changes and improvements may readily be incorporated therein, without departing from the scope of this invention as defined in the annexed claims.

I claim:

1. In a woman's dress having a waist, the combination with the waist, of pleat structures at the sides thereof, each pleat structure comprising a relatively wide interior pleat and two exterior pleats of lesser width adjacent thereto, the

inner edge of the interior pleat and the exterior edges of the exterior pleats being reinforced over their entire length, sleeves provided with the waist, inserts in the sleeves operatively connected with the interior pleats, said pleat structure being adapted to remain normally closed so that the reinforced edges of the exterior pleats are in adjacency with the outer edges of the interior pleat, and is further adapted to be opened and to unfold by the movement of the sleeve insert, induced by moving the wearer's arm either in upward, sidewise or forward directions, and to automatically re-assume its normal, folded position when the strain caused by the arm movement upon the sleeve insert ceases.

2. A garment having two openable front panels and a continuous back panel, the rear and front panels being joined to form shoulder structures of the garment and having arm openings at their upper ends, sleeves attached to the arm openings; the front and rear panels being joined along their sides by an accordion arrangement of pleats, that pleat arrangement consisting of two exterior pleats and a central interior pleat formed between the exterior pleats, each of the exterior pleats comprising inwardly and outwardly directed sections, the central pleat having two normally adjacent, much wider outwardly directed sections, the interior edges of which are joined and stitch-reinforced; diamond-shaped inserts provided at the arm pit portions of the sleeves, the two outward edges of the inserts being attached to the sleeves, the interior edges of the inserts being secured to the two sections and their joined edges of the central pleat.

3. In a woman's dress, an upper garment portion above the waistline comprising two continuous front panels and a continuous back panel, both front panels and the back panel having stitch-reinforced outer edges, shoulder structures formed by the joined upper parts of the front panels and the back panel, sleeves extending from the shoulder structures, the portions of the edge reinforcements of the joined front and back panels passing over and being affixed to the outer top edges of the shoulder structures and to the upper edges of the sleeves, self-closing pleat structures connecting the front panels with the back panel and forming the sides of the upper garment portion above the waistline and extending both in front and in back from approximately midway of the shoulder structure downwardly and comprising a relatively wide interior pleat and two adjacent exterior pleats, substantially diamond-shaped inserts provided at the arm pits of the sleeves and connecting the latter with the interior pleats, the inner joined edges of the interior pleat and the outer edges of the exterior pleats being reinforced by stitching.

4. In a woman's dress as per claim 3, the reinforcements at the outer edges of the exterior pleats coinciding with the stitch-reinforcements at the outer edges of the front and back panels of the upper garment portion.

5. In a woman's dress having waist and skirt portions forming continuations of each other, said dress being composed of two continuous front panels and a continuous back panel, an accordion-shaped pleat structure connecting the front panels with the back panel and forming the sides of the waist, said pleat structures comprising a relatively deep interior pleat, composed of two normally adjacent pleat sections joined at their inner edges, and two adjacent exterior pleats of lesser depth, the edges of the front panels and

of the back panel forming the outer edges of the exterior pleats stitch-reinforcements provided at these outer edges of the exterior pleats and at the inner joined edges of the sections of the interior pleat, the front panels and the rear panel being connected to form garment shoulders, sleeve structures depending from the latter, inserts arranged at the arm pit of the sleeves and being operatively connected with the sections of the interior pleat and their joined, stitch-reinforced inner edges.
